ATTORNEYS

UNITED STATES PATENT OFFICE.

MARCUS B. BEHRMAN, OF BALTIMORE, MARYLAND.

TRUNK.

SPECIFICATION forming part of Letters Patent No. 779,345, dated January 3, 1905.

Application filed April 7, 1904. Serial No. 202,028.

To all whom it may concern:

Be it known that I, MARCUS B. BEHRMAN, a citizen of the United States, residing at Baltimore, in the State of Maryland, have made certain new and useful Improvements in Trunks, of which the following is a specification.

My invention is an improvement in packing-cases—such, for instance, as trunks, dress-suit cases, shipping-cases, delivery-cases such as merchant tailors use to deliver clothing, cases for ladies' wearing-apparel, and similar cases wherein it is desired to pack articles of clothing; and the invention has for an object, among others, to provide a novel construction by which the clothing may be held from movement in the case and may be preserved in the position in which it is placed in the case, so that it will not move about and become wrinkled and otherwise disarranged; and the invention consists in certain novel constructions and combinations of parts, as will be herein-after described and claimed.

In the accompanying drawings, which represent my invention embodied in a trunk-tray, Figure 1 is a top plan view of a tray provided with my improvements, the cover being partially broken away. Fig. 2 is a vertical longitudinal section of such tray. Fig. 3 is a detail section on about line 3 3 of Fig. 1. Fig. 4 is a detail perspective view of the presser-bar, partly broken away at the middle and showing the spring devices at the opposite ends of such bar. Fig. 5 is a detail perspective view of one of the keeper-plates in connection with a portion of the side of the case. Fig. 6 is a detail perspective view of the seat-plate for use opposite that shown in Fig. 5, and Fig. 7 shows a somewhat different form of presser-bar from that illustrated in Fig. 4.

While I have illustrated my invention in connection with a trunk-tray, it will be understood that I do not desire to be limited to such use of the invention, as it may be employed in other constructions—such, for instance, as before referred to. I will therefore refer to the construction with which my invention is employed as a "body" or "case" A, intending

by such term to include a trunk-body, a trunk-tray, a packing-case, full-dress-suit case, or package for use in delivery of clothes. This body or case A is provided at one end with an upright series of hooks B for engagement by a clothes hanger-frame C, as shown in Fig. 1.

At the opposite sides of the box or case I provide plates D and D', which are alike, except that the seats d in the plate D are round openings, while the seats d' in the plate D' are slotted at D², so that the keeper-bar E may be inserted endwise at one end in the seats d and be slipped laterally at its other end into the seats d' through the slots d², as will be understood from Figs. 1, 2, and 3 of the drawings. In order to space the plates D and D' away from the sides of the case A, I secure upright spacing-bars F to the inner sides of the case A and support the plates D and D' on such spacing-bars F in such manner that the plates project beyond the spacing-bars F toward the end of the body A provided with hooks B, so that the keeper-bar E will be securely held in the seats d and d' against movement toward the end of the case A opposite the hooks B, as will be understood from Figs. 1 and 2 of the drawings. Below the plates D and D' or on the side of said plates opposite the hooks B, I provide keeper-plates G g, one of which is provided with undercut slots G', opening in the reverse direction to the seats d' and arranged for engagement by the pivoted tongue and latch-plate at one end 8 of the presser-bar H, presently described, and the other, g, having openings g' for the projecting tongue at the other end of said presser-bar. These plates G g are spaced away from the inner sides of the body or case A like 85 the plates D and D' and are preferably supported on the inner faces of upright bars G², whose outer faces are secured to a base-plate G³, which is slotted horizontally at G⁴ for the passage of the clamping-screw I, which receives the nut I', the edges of the slot G⁴ being slightly turned up at g⁴, forming ribs against which the clamping-nut bears, as will be understood from Fig. 5 of the drawings.

By this construction the keeper-plates G can be adjusted longitudinally within the body or case A in such manner as to properly press upon the garments of different lengths, as 5 will be understood from Figs. 1 and 2 of the drawings.

The presser-bar H is designed to press the garments firmly against the bottom of the case A or against the garments placed below them, 10 and this bar, as shown in Fig. 4, is constructed of spring or other material, being preferably upturned at h near its end and having the outwardly-projecting end portions h' and h'', one end of the presser-bar being provided with a 15 tongue h³ to enter the seats g', and the other end of the presser-bar being slotted at h⁴ to fit on opposite sides of the seat-plate G and having at such end the latch-plate J, which is pivoted at J' at one end and may be swung at 20 its other end into and out of engagement with the slots G' in the seat-plate G. This presser-bar H being of spring material may be made to exert any desired pressure upon the garments. The latch J has a thumb-piece J² near 25 its swinging end and may be readily adjusted into and out of alinement with the bar H in the use of the invention.

It will be noticed that the presser-bar H is made of a length not in excess of the space 30 between the opposite plates G, so that when the tongue h³ is inserted in the slots g' of plate g the presser-bar may be brought squarely down close to the inner side of the opposite slotted plate G and the latch J be swung from 35 the position shown in Fig. 4 to that shown in Fig. 1, in which it engages with its proper slot G'. By this latch it will be noticed I avoid any swinging or horizontal movement 40 of the presser-bar upon the clothing and am able to bring such presser-bar squarely down upon the clothing in order to hold the same as desired. Thus in securing a pair of trousers as shown in Fig. 1 the garments may be properly folded into the desired creases and 45 then folded over the rod E and held at both ends beneath the presser-bar. Ladies' garments may also be held from movement.

In Fig. 7 I show a somewhat different form 50 of presser-bar from that shown in Fig. 4, the presser-bar shown in Fig. 7 having an upwardly-projecting spring-tongue L at one end and a pivoted latch M at its other end, the upper surface of the bar being grooved at M', 55 adjacent to the latch M, to receive the said latch when the latter is adjusted into alinement with the bar and to lock the latch in the recess M' by the upward pressure of the clothing beneath the said presser-bar.

By providing the seats for the rod E and the 60 presser-bar in vertical series any quantity of clothing may be secured in the box or case and firmly held from movement therein.

Having thus described my invention, what I claim as new, and desire to secure by Letters Patent, is—

1. The combination of the body or case, an upright series of hooks at one end thereof for engagement by a clothes hanger-frame, plates at the opposite sides of the case for engagement by the opposite ends of the keeper-bar, 70 the seats in one of said plates opening toward the end of the case provided with the upright series of hooks, the keeper-bar engaging the seats of said plates, keeper-plates secured to the case on opposite sides of said first keeper-plates from the series of hooks, and provided with seats opening in the reverse direction to those in the said first plates, and a presser-bar provided at its ends with means engaging with the seats of the keeper-plates, substantially 75 80 as and for the purposes set forth.

2. The combination with a body or case, of a keeper-bar, plates having seats for said keeper-bar, a presser-bar and plates having seats for said presser-bar, the seats for the 85 keeper-bar being closed in the direction of the presser-bar, substantially as set forth.

3. The combination of the body or case, a pair of plates having seats, a presser-bar arranged to fit between said plates and having 90 at one end a tongue to engage with the seats of one of said plates, and a swinging latch carried by the other end of the presser-bar to engage with the other seat-plate, substantially as set forth.

4. The combination with the body or case, and the opposite seat-plates, of a presser-bar arranged to fit between said plates, and provided at one end with means to engage with the adjacent seat-plate, and the swinging latch 100 arranged to engage with the adjacent seat-plate, substantially as set forth.

5. The combination of the body or case, side plates g having seats for a presser-bar, upright spacing-bars to which said side plates are secured, base-plates secured to said spacing-bars and slotted for the passage of the clamping devices, clamping devices for said base-plates, and a presser-bar having means for engagement with the seat-plates, substantially 110 as set forth.

6. The combination of the body or case, seat-plates adjustable longitudinally within the body or case, means for securing the seat-plates in different adjustments within the 115 body or case, and the presser-bar having means for engagement with the opposite seat-plates, substantially as set forth.

7. In an apparatus substantially as described the combination of the body or case, a presser-bar of spring material having at one end a pivoted latch swinging horizontal into and out of alinement with the presser-bar, and a seat-plate in the body or case for engage- 120

ment by said swinging latch, substantially as set forth.

8. The combination of a body or case, opposite seat-plates arranged therein, one of said plates having slots opening toward the adjacent end of the box or case, a keeper-bar to engage said plates, keeper-plates having the seats of one plate opening toward the adjacent end of the body or case and in the opposite di-

rection to the slots of the other keeper-plate, 10 and the presser-bar having means engaging with said keeper-plates, substantially as set forth.
